VALVE TRUMPET

Davis Shuman, 741 Bradford St., Brooklyn 7, N.Y.

Continuation of application Ser. No. 520,605, July 7, 1955. This application Sept. 17, 1958, Ser. No. 762,197

1 Claim. (Cl. 84—388)

This invention relates to horns and more particularly to valve trumpets.

Heretofore valve trumpets have been made with the bell, valve casings and lead pipe rigidly fixed to one another by means of immovable connections and connecting braces and as a result a relatively small space is available for the trumpeter's left hand and fingers to grip the instrument when it is held in a playing position. When the mouth piece is properly placed on the player's lips the bell is very often pointed directly into the music stand and the trumpeter must turn his head left or right, up or down, or must sometimes raise or lower the stand in order to avoid this condition. Further, when playing loud passages it is perfectly satisfactory to point the bell in a forward direction, but with soft passages it is difficult to keep the volume down in such a position. In addition, the conventional trumpet is so constructed that a person with large hands or a left handed player finds it very awkward to handle the instrument in a normal and easy manner.

I am aware that it has been proposed to provide wind instruments with bells rotatably attached to the bell section in order to direct the music in the desired direction and also that wind instruments have been provided with bells bent from the normal plane of the bell section. These constructions, however, while adaptable to large wind instruments, have not been particularly adaptable to valve trumpets and have not in any event solved the problem of restricted hand space immediately surrounding the valves.

I have now found that these difficulties may be avoided if the entire bell assembly is attached to the remainder of the trumpet in a detachable and rotatable manner so that the bell may be rotated to point in various angular directions in a plurality of planes.

It is accordingly a primary object of the present invention to provide a valve trumpet with a detachable and removable bell assembly which may be conveniently played by a person with large hands or by a person who may be left handed.

It is another object of the invention to provide a valve trumpet having a movable bell assembly which may be positioned and adjusted to various angular directions in a plurality of planes.

It is another object of the invention to provide an improved valve trumpet.

Further objects and advantages of the invention will become apparent upon reference to the following specification and claim and the appended drawings wherein:

2

Figure 1 is a side elevation of a valve trumpet constructed according to my invention;

Figure 2 is a side elevation of a valve trumpet constructed according to my invention with the bell assembly rotated approximately 180° from the position which it occupies in Figure 1;

Figure 3 is a side elevation of a valve trumpet constructed according to my invention with the bell assembly rotated approximately 270° from the position which it occupies in Figure 1; and

Figure 4 is an elevation of the bell assembly of a trumpet constructed according to my invention.

Referring more particularly to the figures of the drawing there is shown in Figure 1 a valve trumpet 10 having a conventional valve casing arrangement 12, lead pipe 14 and mouth piece 16. According to my invention the bell assembly 17, comprising bell 18, bell section 20, bell bow 22 and branch section 26, is formed separately from the rest of the instrument, as may be seen in Figure 4, and is rotatably attached to a tapered ferrule 24 in communication with the valve casing. The branch section 26 of the movable bell assembly is preferably provided with a tapered end which mates with the tapered ferrule 24 and the bell assembly may be locked into position by means of any suitable lock-out arrangement.

While the branch section of conventional trumpets normally lies in the same plane as the axis of the bell and bell section it is a feature of my invention that the branch section 26 is bent slightly out of this plane as may clearly be seen in Figure 4. With this construction and with the rotatable connection at the ferrule 24 the trumpeter may adjust the bell into a large plurality of planes by simply rotating the bell assembly about the ferrule 24. This is clearly shown in Figures 1, 2 and 3 illustrating the bell assembly in three widely separated positions. It will be clear from these figures that a person with large hands or a left handed person may so rotate and position the bell assembly as to leave ample room for either hand to operate the valves in complete freedom. The bell and bell section may be angularly positioned to secure the desired volume or other effects and, as a result of my construction, the conventional brace between the bell section and remainder of the instrument is eliminated so that the bell is free to vibrate much more freely than is usually possible. It will thus be apparent that I have provided a novel valve trumpet having many advantages over the conventional instrument. The instrument may be sold with a number of bells so that the player may select the proper bell for the music played and the acoustics found in the studio, theater or ballroom.

The invention may be embodied in other specific forms without departing from the spirit or essential characteristics thereof. The present embodiment is therefore to be considered in all respects as illustrative and not restrictive, the scope of the invention being indicated by the appended claim rather than by the foregoing description, and all changes which come within the meaning and range of equivalency of the claim are therefore intended to be embraced therein.

This application is a continuation of application Serial No. 520,605 filed July 7, 1955, now abandoned.

What is claimed and desired to be secured by United States Letters Patent is:

In a valve trumpet having a valve casing and a lead pipe connected thereto, valves in said valve casing, a ferrule attached to said valve casing, an integral bell assembly comprising a bell and bell section, said bell and bell section having a common longitudinal axis generally normal to the axes of said valves, said bell and bell section being of a total length substantially equal to the total length of said trumpet, a bell bow connected at one end to said bell section, and a branch section attached to the other end of said bell bow, said bell bow having a bend out of a plane containing the axis of said bell and bell section, said branch section being rotatably attached

to said ferrule so as to be rotatable beneath said valve casing about its own axis through the greater part of a circle.
